DESIGN FOR A WIRE DOOR RACK OR SIMILAR ARTICLE

Edward Willard Gentz, Jackson, Mich., assignor to The Sparks-Withington Company, Jackson,
Mich., a corporation of Ohio

Application July 19, 1935, Serial No. 57,728

Term of patent 7 years

To all whom it may concern:

Be it known that I, Edward Willard Gentz, a citizen of the United States, residing at Jackson, in the county of Jackson and State of Michigan, have invented a new, original, and ornamental Design for a Wire Door Rack or Similar Article, of which the following is a specification, reference being had to the accompanying drawing, forming part thereof.

The figure is a perspective view of a wire door rack or similar article showing my new design.

I claim:

The ornamental design for a wire door rack or similar article as shown.

In witness whereof, I have hereunto set my hand this 3d day of July, 1935.

EDWARD WILLARD GENTZ.
